ORNAMENTAL RAILING

Louis Blum and William J. Horgan, Jr., Pittsburgh, Pa., assignors to Blumcraft of Pittsburgh, Pittsburgh, Pa., a firm

Filed July 28, 1965, Ser. No. 86,319

Term of patent 14 years

(Cl. D13—7)

F/G. 1

FIG. 1 is a perspective view of an ornamental railing embodying our new design;

FIG. 2 is a perspective view of the ornamental railing post and a fragmentary portion of the handrail;

FIG. 3 is a perspective view of the ornamental railing post and a fragmentary portion of the handrail;

FIG. 4 is a perspective of another railing embodying our new design.

The broken line portions in FIGS. 1 and 4 are disclosed for illustrative purposes only.

We claim:

The ornamental design for an ornamental railing, as shown and described.
